UNITED STATES PATENT OFFICE.

HENRY C. HOPKINS, JR., OF COVINGTON, KENTUCKY.

CLOTHES-WRINGER.

SPECIFICATION forming part of Letters Patent No. 356,641, dated January 25, 1887.

Application filed February 15, 1886. Serial No. 192,034. (No model.)

To all whom it may concern:

Be it known that I, HENRY C. HOPKINS, Jr., a resident of Covington, in the county of Kenton and State of Kentucky, have invented certain new and useful Improvements in Clothes-Wringers, of which the following is a specification.

My invention relates to an improvement in clothes-wringers; and it consists in the construction and combination of parts hereinafter described and claimed.

Figure 1 represents a broken elevation of my improvement. Fig. 2 is a similar view, showing the rolls relieved of pressure. Fig. 15 3 is a detail view of the connecting-rod. Fig. 4 is a detail view of one of the end pieces of the frame.

A represents the brackets by which the wringer is attached to a tub. 20 C D represent the ordinary U-springs. The forward ends of the springs are made of semi-circular form, to serve as bearings for the roller-shafts E E'.

F represents a frame end piece, one of which 25 is placed at each end of the wringer-rolls. 1 2 represent the wringer-rolls.

3 represents a vertical slot in the lower part of each end piece, F, through which the ends of the lower shaft project.

30 4 represents a horizontally-inclined slot in the end piece, F, through which the ends of the upper shaft project.

5 represents flanges which project beyond the peripheries of the rolls.

35 6 represents a socket, into which the tenon on the cross-piece 7 enters.

Each end of the wringer is provided with a similar frame-piece, F, each of which is the counterpart of the other, one being right and 40 the other left hand.

8 represents a lug projecting out from one side of the end piece, F, and under the upper arm of the spring C D.

The rollers and shafts are secured to the 45 wringer in the ordinary manner, and their ends are placed in the slots 3 and 4 and held in position by the spring-arms C and D, which tend to draw the shafts together and hold them normally in the position shown in Fig. 1.

50 When it is desired to relax the pressure of the rolls, pressure is applied to the cross-piece 7, pushing it forward, the lower end of

the frame-piece F turning on the shaft E, which serves as a fulcrum, and the upper end of the frame-piece F sliding laterally on the 55 shaft E'. The slots 4, which are slightly inclined from the horizontal, move over the shaft E into the position shown in Fig. 2. During this movement the lug 8 strikes the arm D of the spring upon its under side, causing said 60 arm to rise and relieve the rolls from pressure, as shown in said Fig. 2.

When it is desired to use the wringer, pressure is applied to the cross-piece 7, and the parts are brought back into the position shown 65 in Fig. 1.

This form of construction is very cheap and simple, and it enables the cross-piece which is used to steady the frame end pieces, F, to be used as a handle for pushing the lug 8 against 7c the arms of the springs to relieve the rolls.

It will be seen that by giving the slots 4 a slight inclination from the horizontal the rolls 1 and 2 will be withdrawn from contact when the end frames, F, are tilted forward, as shown 75 in Fig. 2. At the same time the slots 3, which receive the journals of the lower roll, amply provide for the play of the rolls when the wringer is in use, since, when heavy articles pass between the rolls, the spring-arms C D 80 will spread, the upper roll and end frames lifting and the lower ends of slots 3 approaching the journals of the lower roll.

Having described my invention, what I claim as new, and desire to secure by Letters Patent, 85 is—

1. The combination, with the wringer-rolls and their shafts E E' and springs C D, of the frame-pieces F, having vertical slots 3, which receive the journals of the lower roll, and being provided with the inclined slots 4 and lugs 8, substantially as described.

2. The combination of the wringer-rolls having shafts E E', the frame-pieces F, having slots 3 and 4, sockets 6, and lugs 8, the connecting-rod 7, and the springs C D, substantially as described.

In testimony whereof I have hereunto set my hand.

HENRY C. HOPKINS, JR.
